(57) **CLAIM**

I claim the ornamental design for a medical rod cutter, as shown and described.

DESCRIPTION

FIG. 1 is a front left side perspective view of a medical rod cutter showing my new design;

FIG. 2 is a front right side perspective view thereof;

FIG. 3 is a left side elevation view thereof;

FIG. 4 is a right side elevation view thereof;

FIG. 5 is a top plan view thereof;

FIG. 6 is a bottom plan view thereof;

FIG. 7 is a front elevation view thereof;

FIG. 8 is a rear elevation view thereof; and,

FIG. 9 is a rear left side perspective view thereof in an extended mode.

The broken lines shown in the drawings are for illustrative purposes only and form no part of the claimed design.
